(57) **CLAIM**

The ornamental design for a brake light, as shown and described.

DESCRIPTION

FIG. 1 is a front elevation view of a brake light, showing my new design;

FIG. 2 is a rear elevation view thereof;

FIG. 3 is a left side elevation view thereof, the right side elevation view is a mirror image;

FIG. 4 is a top plan view thereof;

FIG. 5 is a bottom plan view thereof;

FIG. 6 is a front perspective view thereof;

FIG. 7 is an additional front perspective view thereof; and, FIG. 8 is a rear perspective view thereof.

The broken lines in the drawings illustrate portions of the brake light that form no part of the claimed design.

1 Claim, 8 Drawing Sheets(56)
